UNITED STATES PATENT OFFICE.

ALPHONSE FERNANDEZ, OF WASHINGTON, DISTRICT OF COLUMBIA.

ILLUMINATED TORPEDO.

1,232,671.

Specification of Letters Patent. Patented July 10, 1917.

Application filed September 20, 1916. Serial No. 121,263.

To all whom it may concern:

Be it known that I, ALPHONSE FERNANDEZ, a subject of the King of Spain, residing at the city of Washington, in the District of Columbia, have invented certain new and useful Improvements in Illuminated Torpedoes; and I do declare the following to be a full, clear, and exact description of the invention, such as will enable others skilled in the art to which it appertains to make and use the same:

My invention aims to provide simple means whereby a body of water may be illuminated in any direction from a ship without disclosing the location of the latter, and to this end I mount a searchlight on a torpedo and provide means for illuminating the light after the torpedo has traveled a distance from the ship from which it was launched. By the use of the improved device, therefore, vessels which are in darkness at night in time of war may send out one or more of the improved torpedoes in the direction of the course they wish to pursue and thus the latter will be illuminated so that the pilot of the vessel will be able to see whether or not hostile craft are in his path.

With the foregoing general object in view, the invention resides in certain novel features of construction and in unique combinations of parts to be hereinafter fully described and claimed, the descriptive matter being supplemented by the accompanying drawing which constitutes a part of this application and in which:

Figure 1 is a side elevation, partly in section of a torpedo constructed in accordance with the invention, showing the position of parts when the device is first launched;

Fig. 2 is a similar view showing the manner in which the switch of the searchlight is closed when the torpedo has traveled a distance from the point at which it was launched;

Figs. 3 and 4 are vertical transverse sections on the planes indicated by the lines 3-3 and 4-4 of Fig. 1;

Fig. 5 is a longitudinal section on the plane of the line 5-5 of Fig. 3, showing the automatically projected center-board which is preferably used on the improved torpedo.

In the drawings the numeral 1 designates a torpedo of the usual or any preferred construction and in some cases it may carry ex-

plosives but since its use is primarily to illuminate a course, the latter will preferably be omitted. The usual engine not shown is mounted in the torpedo 1 and is set in operation automatically in the well known manner when the torpedo is launched, said engine driving the usual propellers 2 and 3 which are disposed between the rear ends of longitudinal vanes 4 at the rear end of the device.

Located preferably at the extreme front end of the torpedo 1 is an electric searchlight 5 having a switch 6 for completing its circuit, the current being supplied by batteries 7 within the torpedo shell. A spring 8 is provided for closing the switch 6 but the latter is normally held open against the tension of said spring by a suitable trigger 9 here shown in the form of a spring having an inclined portion 10 which acts as a cam to assist in releasing the trigger in a manner to be described.

A control member 11 is provided for releasing the trigger 10 when the torpedo has traveled a predetermined distance from the vessel from which it was launched, said member as shown most clearly in Fig. 4 being in the form of a split nut whose two halves are connected by means of a hinge 12 and a thumb screw or the like 13. An operating screw 14 is threaded through the aforesaid split nut and extends longitudinally of the torpedo body as shown clearly in Figs. 1 and 2, said screw being driven slowly by means of appropriate gearing 15 from a shaft 16 operated by the engine of the torpedo. The member 11 preferably includes a pair of depending fingers 17 which travel on opposite sides of a longitudinal guide rod 18 and said member is also provided at its upper end with a laterally extending finger 19, this finger being adapted to engage the cam 10 when rotation of screw 14 has shifted the control member 11 the required amount (see Fig. 2). When this occurs, the trigger 9 is released and the spring 8 immediately closes the switch 6 to illuminate the light 5. By the time the trigger 9 is released the control member 11 runs off of the threads of the screw 14 onto the reduced front end 20 thereof so that continued rotation of the screw as the torpedo travels on its course will produce no injurious effects.

In order to effectively hold the torpedo to its course even though it may at times ride the crests of large waves, an improved means

is provided, this means being in the form of a center-board 21 normally confined in a guideway 22 which extends longitudinally of the torpedo and opens through the lower side thereof, a spring 23 being provided for projecting said center-board automatically when the torpedo leaves the tube from which it is launched. For illustrative purposes, the center-board 21 is shown provided with vertical slots 24 receiving stop pins or the like 25 so as to limit the downward movement of said board but it is to be understood that any other suitable means could well be provided.

15 By providing the center-board 21, the torpedo will be at all times held to its course, it having been found by experience that vanes such as 4 on the rear end of the torpedo are not at all times effective since 20 when the torpedo is riding the crests of waves, the entire rear end thereof is often entirely out of the water, thus permitting the entire device to turn and lose its course. The center-board 21, however, will at all 25 times travel through the water and will thus reliably prevent the torpedo from changing its course.

The improved device constructed as or substantially as shown and described may 30 be used in a number of ways as occasion may demand. For instance, it may be directed from a ship at night in the manner heretofore suggested or if the commander of the vessel wishes to follow a certain course for 35 a period of time he may well connect one end of a cable, say half a mile long to the torpedo and may anchor the other end of said cable to his vessel. Thus after the time switch completes the circuit of the searchlight, the course will be effectively lighted 40 up but the source of light will be at such a point as to prevent hostile craft from ascertaining the location of the vessel under way. This arrangement is also rather ad- 45 vantageous since the torpedo may be retrieved at any time should it be found expedient. Also, should occasion demand, the cable may be cut so that the torpedo will travel faster than the vessel in order to de- 50 coy any enemy ships which may be investigating the traveling light.

The distance which the torpedo is permitted to travel before illumination of the headlight may be regulated by adjusting 55 the control member 11 on the screw 14 before the torpedo is launched, this being permitted by the hinge 12 and set screw 13, the latter being accessible through a door such as that indicated at 26 in Fig. 3. It will be 60 understood that as the member 11 is adjusted toward the trigger 9, the length of

the period during which the light 5 is not illuminated will be increased whereas this period will be increased when the control member is adjusted in the opposite direction. 65

In the drawing, certain specific details have been shown and the same have been herein referred to but it is to be understood that the present showing and description 70 are for illustrative purposes only and that within the scope of the invention as claimed, numerous changes may be made.

I claim:

1. A non-inflammable torpedo having 75 thereon a searchlight, and means for automatically illuminating said light when the torpedo has traveled a distance from the point at which it was launched.

2. A torpedo having thereon an electric 80 searchlight, a switch for completing the circuit of said light, means for closing said switch, a trigger for holding said switch open against the action of the closing means, and means for releasing said trigger when 85 the torpedo has traveled a distance from the point at which it was launched.

3. A torpedo having thereon an electric searchlight, a switch for completing the circuit of said light, means for closing said 90 switch, a trigger for holding said switch open against the action of the closing means, a control member for tripping the trigger, and a screw for moving said member from inoperative to operative position as the tor- 95pedo travels on its course.

4. A torpedo having thereon an electric searchlight, a switch for completing the circuit of said light, a spring for closing said switch, a trigger for holding the switch open 100 against the tension of said spring, said trigger having a releasing cam, a control member having means to engage said cam to release the trigger, and a screw for moving said control member from inoperative to op- 105erative position as the torpedo travels on its course.

5. A torpedo having in its pointed front end a substantially parabolic reflector whose front side is closed by a lens, an electric 110 light in said reflector, a source of electricity in said torpedo, and a time switch in circuit with said light and source for illuminating the former when the torpedo has traveled a distance from the launching point. 115

In testimony whereof I have hereunto set my hand in the presence of two subscribing witnesses.

ALPHONSE FERNANDEZ.
